UNITED STATES PATENT OFFICE.

MILO D. BEACH, OF LITCHFIELD, CONNECTICUT.

HILLSIDE-PLOW.

SPECIFICATION forming part of Letters Patent No. 399,000, dated March 5, 1889.

Application filed November 16, 1888. Serial No. 291,025. (No model.)

To all whom it may concern:

Be it known that I, MILO D. BEACH, a citizen of the United States, residing at Litchfield, in the county of Litchfield and State of Connecticut, have invented certain new and useful Improvements in Hillside-Plows; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to plows; and it consists in certain improvements in that class known as "swivel" or "hillside" plows, whereby when the plowshare and mold-board are reversed the jointer or colter and the clevis 15 will be automatically shifted. The clevis-hook is also made laterally adjustable, so that the side draft caused by the clevis being inclined to one side of the center line of the beam may be increased when the clevis stands on one side and decreased when it stands on the other side. These results are accomplished 20 by the mechanism shown in the drawings, in which—

Figure 1 is a side elevation of an iron-beam 25 plow embodying my improvements. Fig. 2 is a vertical longitudinal section of the working parts. Fig. 3 is a horizontal section through the shaft. Fig. 4 is a vertical cross-section through the handles and the duplex hook. Fig. 5 is a view of the double eccentric for 30 shifting the jointer. Fig. 6 shows a modified form of the same for shifting the colter. Figs. 7, 8, and 9 illustrate the duplex hook. Fig. 10 is a cross-section of the tubular bearing and the colter, taken on line $x-x$, Fig. 14. Fig. 11 shows the sector-gear. Fig. 12 is a 35 cross-section of the jointer on line $y-y$, Fig. 2. Fig. 13 is a plan of the crank-head. Fig. 14 is a view of the colter; and Fig. 15 is a 40 cross-section of the beam on line $z-z$, Fig. 1.

The same letters refer to the same parts in all the figures.

The beam and standard A and the swiveling plowshare and mold-board B are of any convenient design. The handles C are bolted to the standard at c , and also to a cross-bar, D, which is fastened by a bolt, d , to a lug or ear, a ,

projecting rearwardly from the standard. Between the handles is pivoted the duplex hook E, which is composed of a hub, e , having two arms, e' , meeting the hub at an obtuse angle. On the outer end of each arm is an upwardly-turned hook, e^2 , having its upper edge downwardly inclined toward the rear, as shown in Fig. 8. Along the upper side of each arm runs a rounded rib, e^3 . From the upper face of the hub project one or more studs, e^4 , which enter corresponding holes in the end of a headed sleeve, F, and thus lock the hook and sleeve together. Other means of accomplishing this will be readily suggested. The sleeve is cylindrical and fits into a bearing formed in the cross-bar D. The upper end of the sleeve is flattened on opposite sides to enter an oblong slot, g , cut in the plate G, which rests on the upper face of the cross-bar D. Through the hub e and the sleeve F passes a bolt, H, which has a broad flat head, h , bearing against the under side of the hook E. The opening in the hub e is larger than the bolt, so that the hub is loose on the bolt, which extends considerably above the plate G, and carries a cap, h' , which may be integral with the nut h^2 , or separate from it, as desired.

Between the cap and the plate G is seated a helical spring, H', encircling the bolt, which is thus free to slide axially in the sleeve F, but is normally held with its head holding the hook E in place against the sleeve. The hook can, however, be sprung slightly away from the sleeve, so that when swung from an opposite position to the other it may ride under one of the small lugs d' , which depend from the under side of the cross-bar D and serve to lock the hook in place. The lugs d' and the ribs e^3 are rounded, as shown in Fig. 7, so as to readily be engaged or disengaged by the application of sufficient force.

On each under side of the mold-board is a catch or lug, b , having one face beveled, as shown in Fig. 4. The edge of the lug is also inclined, to correspond with the edge of the hook e^2 , as shown in Fig. 8. When the plow is to be reversed, the plowman pushes the projecting arm of the double hook E with his foot, which disengages said hook from the lug b on the mold-board and from the lug d' on the cross-bar and throws it around into its other position, where it is locked by the lug

d' on that side. The plowshare and mold-board are then reversed, and as they come up into position the catch *b* strikes the curved end of the hook *e*² and depresses the arm *e'* into the position shown in dotted lines in Fig. 4, when, the catch having passed beyond the hook, the arm again springs up into place and locks the mold-board. The spring *H'* allows the hook to have sufficient play to act in this manner, and the inclined edges of the hook *e*² and the lug *b* have a tendency on meeting to throw the arm *e'* forward and so avoid any danger of disengaging it from the lug *d'*.

When the duplex hook is swung from one side to the other, it oscillates the sleeve *F* and the plate *G*. The front edge of said plate is a segment of a circle struck from the center of the sleeve *F*, and is cut into bevel gear-teeth *g'*. These mesh with a sector-gear wheel, *I'*, on a shaft, *I*, which is stepped in a bearing, *d*², preferably formed in the cross-bar *D*, and extends upward along the back of the standard, as shown, its upper end being received in a semi-cylindrical socket, *j*, formed at one end of a double eccentric, *J*. The shaft *I* is secured in the socket by a bolt, as shown. The semi-cylindrical form of the socket allows the shaft *I* to be stepped in the bearing *d*², and then dropped laterally into the socket and fastened. At the end of the double eccentric *J* is formed a cup-shaped hub, *j'*, cylindrical on the outside. The axis of this hub is in line with the axis of the socket *j* and the shaft *I*, so that the hub revolves concentrically with the shaft *I*.

The double eccentric *J* consists of a cylindrical shaft united to the socket *j* at one end and to the hub *j'* at the other, but so placed with its ends on opposite sides of the axis of the shaft *I* and hub *j'* that the axis of the eccentric *J* crosses the axis of the shaft *I* and hub *j'* preferably about midway of the eccentric *J*. When the shaft *I* is rotated, the ends of the eccentric *J* will describe small circles around the axis of the shaft. The hub *j'* is held in a cylindrical bearing formed in a horn, *A'*, which may be cast integral with the beam *A*, or may be attached to it.

The jointer is provided with a stem, *K*, fitting in a tubular bearing, *A*², formed in the beam *A'*. A transverse bolt, *a'*, engages with a groove, *k*, cut partially around the stem *K*, and prevents any endwise motion of said stem in its bearing. In the upper end of the stem is a diametrical slot, *k'*, whose width is slightly greater than the diameter of the double eccentric *J*, which is engaged with the slot, as shown in Figs. 2 and 3. The axial lines of the shaft *I*, the eccentric *J*, and the jointer-stem *K* all intersect at the point *X*, Fig. 3.

Upon revolving the shaft *I* the vibration of the double eccentric causes the stem *K* to oscillate in its bearing, the angular movement being twice the angle between the axes of the shaft *I* and the eccentric.

To the lower end of the jointer-stem is at-

tached the jointer, composed of a socketed head, *K'*, provided with a set-screw, *k*², engaging with suitable depressions in the stem *K* for the purpose of adjusting the jointer up and down on the stem. To the head *K'* are secured a suitable point and flaring wings or mold-boards, as shown, whereby the jointer is enabled to slice off the turf in advance of the plowshare whichever way the furrow is being turned. A single mold-board jointer may be used, if desired. When the duplex hook *E* is thrown from one side to the other, the sector-gears will be operated, and they are so proportioned that the shaft *I* is thereby given a half-revolution. This is sufficient to throw the point of the jointer over to the side opposite to the mold-board of the plow in a position to properly cut the turf.

In order to automatically swing the clevis to properly adjust the draft of the plow, a shaft, *L*, is mounted in a tubular bearing, *A*³, cored out in the plow-beam. The rear end of this shaft projects into the cup-shaped hub *j'*, where a slot, *l*, in the shaft engages with a pin, *j*³, passing diametrically across the hub. The slot and bolt constitute a universal joint, by which the motion of the shaft *I* is communicated to the shaft *L*.

In the forward end of the shaft *L* is a slot, *l'*, which engages with a pin, *m*, diametrically crossing a cavity in the end of the short horizontal shaft *M*, mounted in a tubular bearing, *A*⁴, cored out in the beam *A*. The shaft *M* projects out from the end of the plow-beam and carries a flat head, *M'*, the front edge of which is a curve. In each side of the head is cut a groove, *m'*, concentric with and parallel to the curved edge, leaving a flange, *m*², on each side of the head. A dog, *N*, having a T-shaped slot fitting the flange and the grooves, is adjustable along the head by means of the set-screw *n*. From the front of the dog projects a cylindrical nose, *N'*.

The clevis *O* is U-shaped, and is pivoted to swing horizontally by means of the bolts *P*, which are provided with suitable nuts, *p*, received in slots in the web of the beam *A*. The curve of the head *M'* is struck from the axis of the bolts *P* as a center. In the inner face of the clevis, which has the same curvature as the head *M'*, is a groove, *o*, which engages with the nose *N'* of the dog *N*.

When the nose *N'* lies in the axis of the shaft *M*, it will have no effect upon the clevis when the shaft is rotated; but if the dog is adjusted to one side or the other along the head *M'*, then when the shaft is rotated the nose *N'* acts as a crank-pin and throws the clevis to one side or the other, and to an extent corresponding with the distance of the nose from the axis of the shaft *M*. In this way the angle of the clevis to the line of draft can be regulated with great nicety, and is certain to give exactly the same amount of side draft in both positions of the plowshare and mold-board. The clevis is automatically shifted at the same time with the jointer and

by the single operation of throwing the duplex hook from one side to the other. Under some circumstances, however, it may be desirable or necessary to give more side draft when running the plow in one direction than when running it in the opposite direction. To accomplish this, the clevis-hook Q is attached to the clevis O by a bolt, q, passing loosely through one of the holes o² in the head of the clevis, and the sides of the clevis-head are chamfered off toward the front and rear from a line just back of the bolt-holes, as shown in Fig. 3. This construction permits the clevis-hook to be laterally vibrated, and it is locked in any desired relation to the clevis by means of intermeshing teeth or corrugations o³ q', formed, respectively, on the front edge of the clevis and the inner face of the slot in the clevis-hook. These teeth run vertically the entire length of the surfaces in which they are formed. To adjust the hook Q, the bolt q is removed, the hook is pulled slightly away from the clevis, moved laterally the required amount, and then pushed back to engage its teeth q' with the teeth o³ of the clevis and bring the bolt-holes into line, so that bolt q may be replaced. This adjustment of the clevis-hook will increase the side draft when the clevis stands on one side and reduce it when the clevis is reversed. The side draft can therefore be regulated with great exactness to suit the varying conditions under which the plow is used. A colter may be substituted for the jointer, if desired. It is shown in the dotted lines in Figs. 1 and 2 and in full lines in Fig. 14. Fig. 6 shows the eccentric for shifting the colter, and Fig. 11 is a cross-section of the colter where it enters the tubular bearing A². The stem R of the colter tapers off toward the top, so as to be able to vibrate sidewise in the bearing. In front of the tubular bearing A² is formed a recess, a² to receive the upper part of the flat blade R' of the colter. The eccentric J', which shifts the colter, is single instead of double, and has a greater throw at its rear end than in front, as indicated by the positions of its axial line relative to the axial line of rotation. A double motion is thus imparted to the colter—one of vibration laterally in the bearing and one of partial revolution on its axis. The vibratory motion throws the point of the colter into line with the plow-point. The rotatory movement brings up the edge of the colter into a nearly vertical plane, and thereby counteracts the tendency of the vibratory motion to tilt the colter out of an upright position. The point of the colter lies in the axis of revolution of the stem R, and is therefore not affected by the rotatory motion.

It will be noticed that the eccentrics J and J' and the adjustable crank-pin N' are so disposed as to be on a dead-center when the jointer or colter and the clevis occupy their working positions, so that the eccentrics and the pin are in the best position to resist strains, and are relieved from all danger of being

thrown out of their positions by the stems of the jointer or colter and the head of the clevis.

Having thus described my invention, what I claim, and desire to secure by Letters Patent, is—

1. The combination, with a reversible plow provided with a duplex hook and having a shifting jointer or colter and a laterally-movable clevis, of suitable crank-like devices for operating said jointer or colter and the clevis and connections between said cranks and duplex hook, substantially as described, whereby when the hook is turned the jointer or colter and the clevis will be shifted, as and for the purpose set forth. 75

2. The combination, with a reversible plow provided with a duplex hook and having a shifting jointer or colter and a laterally-movable clevis, of an eccentric for operating the jointer or colter and a crank-pin for operating the clevis, connected shafts carrying said eccentric and crank-pin, and means, substantially as described, for imparting the motion 90 of the duplex hook to the shafts, as and for the purpose set forth. 85

3. The combination, with a reversible plow provided with a duplex hook and having a shifting jointer or colter and a laterally-movable clevis, of a shaft carrying a sector-gear and an eccentric for operating the jointer, and connected with a shaft carrying an adjustable crank-pin for operating the clevis, and a sector-gear secured to the duplex hook 95 and meshing with the aforesaid gear, whereby when the duplex hook is reversed the shafts will be rotated, substantially as and for the purpose set forth. 100

4. The combination, with a reversible plow, 105 of a duplex hook loosely pivoted on an axially-yielding bolt and having its hooks turned upwardly on its upper side, so that when locking with the lugs on the mold-board its arms move downward in a plane at right angles to 110 their plane of revolution without any backward movement, substantially as described.

5. The combination, with a reversible plow, 115 of a cross-bar, D, attached thereto and provided with the lugs d', and a duplex hook, E, having upwardly-turned hooks e², pivotally supported on the bar between the lugs by means of an axially-yielding bolt, and having ribs e³ for engaging the lugs d', substantially as described. 120

6. The combination, with a reversible plow having catches b made with inclined edges, of a duplex hook, E, having upwardly-turned hooks e² provided with similarly-inclined edges, substantially as described. 125

7. The combination, with a reversible plow having a shifting jointer or colter, of the cross-bar D, the sleeve F, mounted therein and carrying the sector-gear G, the duplex hook attached to the sleeve, and the shaft I, carrying 130 the sector-gear I', meshing with the gear G, and provided with a crank-like device for operating the jointer or colter, substantially as described.

8. The combination, with a rotatable jointer or colter stem having a diametrical slot, of an eccentric shaft passing through the slot and means for rotating the shaft, substantially as described. 5
9. The combination, with a jointer or colter stem capable of rotation and lateral vibration and having a diametrical slot, of an eccentric shaft passing through the slot and means for rotating the shaft, substantially as described. 10
10. The combination, with a reversible plow, of a colter having a stem capable of rotation and lateral vibration and a blade having its point lying in the axial line of the stem and its cutting-edge diverging from said line in front or rear of the same, and means for simultaneously rotating and vibrating the colter-stem, substantially as described. 15
11. The combination, with the shaft I, of the eccentric provided with a semi-cylindrical socket, j, and a hub, j', substantially as described. 20
12. The combination, with the shaft I, of the rotatable jointer or colter stem and the eccentric shown and described, consisting of a socket, j, a hub, j', and a short straight cylindrical shaft uniting the socket and hub and having its axial line at an angle to the axial line of the socket and hub, substantially as described. 25
13. The combination, with a clevis, O, having a groove, o, of a crank-pin engaging with said groove and means, substantially as described, for actuating the crank-pin, as and for the purpose set forth. 30
14. The combination, with a plow-beam, of the shaft M, carrying the curved head M', the dog N, adjustable on the head, the clevis O, engaged by the dog, and means for rotating the shaft, substantially as described. 40
15. The combination, with the shaft M, carrying the curved head M', having the grooves m', of the dog N, adjustable along the grooves m' and having a nose, N', the clevis O, having a groove, o, and means for rotating the shaft M, substantially as described. 45
16. The combination, with the laterally-adjustable clevis O, having chamfered sides, and vertical teeth o², extending the entire length 50 of its front edge, of the clevis-hook Q, having the vertical teeth q', intermeshing with the teeth o² when the hook is attached to the clevis, substantially as described. 55
17. The combination, with the laterally-adjustable clevis O, of the clevis-hook Q, pivoted thereto by a horizontally-arranged bolt, the front edge of the clevis and the rear end of the clevis-hook having vertical teeth which intermesh when the hook is bolted to the clevis, whereby the hook is capable of lateral adjustment with reference to the clevis, substantially as set forth. 60
18. An iron plow-beam provided with the tubular bearing A² for a jointer or colter stem 65 and tubular bearings A³ A⁴ for shafting, said bearings being cored out in the beam, substantially as described.
19. The combination, with a reversible plow having a shifting jointer or colter, of a crank-like device for operating the same, adapted to make a half-revolution when shifting the jointer or colter and to stand on a dead-center when the jointer or colter is in either of its working positions, whereby the crank-shaft is relieved of all torsional strain, substantially as described. 70
20. The combination, with a reversible plow having a laterally-adjustable clevis, of a crank-like device for shifting said clevis, adapted to make a half-revolution in so doing and to stand on a dead-center when the clevis is in either of its working positions, whereby the crank-like device is best enabled to resist the strain upon the clevis, substantially as described. 75
- In testimony whereof I affix my signature in presence of two witnesses.
